UNITED STATES PATENT OFFICE.

GEORGE BITHEL PRICE, OF SALT LAKE CITY, UTAH.

DEMOUNTABLE SPRING COVERING AND OILER.

1,381,010.

Specification of Letters Patent. Patented June 7, 1921.

Application filed April 17, 1920. Serial No. 374,779.

To all whom it may concern:

Be it known that I, GEORGE B. PRICE, a citizen of the United States, residing at Salt Lake City, in the county of Salt Lake and State of Utah, have invented new and useful Improvements in Demountable Spring Coverings and Oilers, of which the following is a specification.

This invention relates to an improved spring boot and oiler and is an improvement upon a patent granted to me, May 5, 1919, and numbered 1,304,366.

An object of the present invention is the provision of a boot and oiler, which will protect the leaves of the spring from dust, water and mud and will in addition provide means for the application of lubrication between the leaves of the spring and prevent the oil and grease from becoming mixed with sand and earth and from gumming, cutting or otherwise injuring the spring.

A particular object of the present invention is the provision of a novel means and for maintaining a lubricant for conducting the same to the various portions of the spring, the lubricant container or reservoir also serving to build up the spring substantially even with the spring clip and thereby improve the appearance of the covering or boot, while the latter acts to protect the spring against any injurious material or matter.

Other objects and advantages of the invention will appear as the following description is read in connection with the accompanying drawings.

In the drawings:—

Figure 1 is a fragmentary elevation of the vehicle spring with the invention applied thereto.

Fig. 2 is a longitudinal sectional view showing the manner of securing the lubricant container or reservoir in position.

Fig. 3 is a transverse section taken on a line with a lubricant opening.

Fig. 4 is a detailed inside plan of the invention with a lubricant container removed.

Fig. 5 is a detailed perspective view of the lubricant container.

Fig. 6 is a view showing the invention applied to a spring, with the outer flap of the boot unfastened.

Fig. 7 is a view similar to Fig. 1 but showing a modified form of the invention.

Fig. 8 is a longitudinal sectional view of the same.

Fig. 9 is a transverse section taken on a line with the lubricant opening.

Fig. 10 is an inside plan view of the boot shown in Figs. 7, 8 and 9, with a lubricant container removed.

Referring to the drawings in detail, and more particularly to Figs. 1 to 6 inclusive the reference character 10 indicates a vehicle spring and 11 the usual spring clip. 65 The invention which is shown applied to the spring is in the form of a boot, preferably constructed from a strip of flexible material, which is also water proof and which surrounds the spring and acts as a protector 70 therefor. The strip of material of which the boot is formed is indicated at 12 and has its marginal edges turned over or hemmed as shown at 13, while secured along one edge beneath the hem is a strip of suitable absorbent material 14, such as canton flannel or the like. This material is also secured centrally of the boot by stitches 15 and one edge of the absorbent lining 14 is left free to provide a flap 16. 80

Secured to the strip 12 is a flap 17, which is preferably formed of the same material as the strip 12 and this strip has its edges turned over and hemmed as shown at 18.

For the purpose of securing the boot in 85 position, the opposite side edges of the strip 12 are provided with spaced eyelets 19 for the reception of a suitable lacing 20 and when the boot is in position upon the spring, this lacing will be arranged along the one 90 side edge of the spring as shown in the drawing. In addition to this flap 17, the boot or the strip 12 is provided with a relatively narrow flap 21 and this flap and the flap 17 are both provided along their edges 95 with spaced eyelets 22, which receive a suitable lacing 23 and which is arranged beneath the bottom of the spring. By this means the spring is entirely covered and for the purpose of providing a lubricant so 100 that the spring will act properly, the boot incloses a pad 24 of suitable absorbent material, which forms a lubricant container and as this pad is relatively thick, a considerable amount of lubricant will be held. 105

In addition the pad 24 after it has been secured in position between the spring and boot, acts to build up the spring adjacent the spring clip so as to present a neat and attractive appearance. After the pad has 110 been saturated with lubricating oil, the absorbent material 14 will act as a wick to

conduct the lubricant to the various leaves of the spring.

In order to supply lubricant to the pad 24 without removing the boot, the said boot is 5 provided with an opening 25, preferably surrounded by a gromet 26, so that the end of an oil can may be inserted through the gromet and oil supplied to the pad 24. In 10 addition the gromet 26 serves to fasten a cup-like receptacle 27 to the inside of the boot, while the pad 24 is provided with an opening 28 to receive this receptacle. The latter is preferably notched as shown at 29, so that the oil may find ready access to the 15 pad 24. The opening 25 is preferably covered by a flap 30, one end of which is secured to the boot and the opposite end provided with one member of a snap fastener by means of which the free end of the flap may 20 be secured over the opening.

In the form of the invention shown in Figs. 7 to 10, the boot is formed of a strip of flexible water proof material 31, which is bolted over and hemmed along its marginal 25 edges and is provided along its opposite side edges with eyelets 32. It is further provided with a lining absorbent material 33, one end of which is free to provide a flap 34, which is adapted to be wrapped over the pad 30 of absorbent material 35, similar to the pad 24 in the manner of wrapping the same as shown in connection with the previously described form of the invention.

The strip of material 31 which forms the 35 modified form of boot has secured thereto a flap 35, this flap being secured only along one edge as indicated at 36, so as to provide a free flap to be wrapped over the flap 34 and around the absorbent pad. The boot is 40 then laced along the bottom of the spring as illustrated.

Like the previously described form of the invention, there is provided a filling open-

ing, which is surrounded by a gromet 37 and this gromet has secured thereto a cup-like 45 receptacle 38 through which lubricant is supplied to the pad or container. To protect the oil opening, there is provided a closure 39 and secured to this closure is a disk 40, by means of a rod or wire 41. Interposed 50 between the closure 49 and the disk 40 is a coil spring 42, the latter being seated within the cup-like receptacle 38 and acting to draw the closure tightly over the filling opening.

The invention is susceptible of various other changes in its form, proportion and minor details of construction and the right is herein reserved to make such changes as properly fall within the scope of the appended claims.

Having described the invention, what is claimed is:—

1. A spring boot made of flexible material adapted to be wrapped around a spring, a lubricant container positioned within the boot, said boot having an opening therein for access to the container and spring actuated protecting means for said opening.

2. A spring boot formed of flexible material adapted to surround a spring, a relatively thick pad of absorbent material within the boot to provide a lubricant container or reservoir, said boot having an opening therein for supplying lubricant to the container and a cup-like receptacle secured 75 around said opening and positioned within an opening in the absorbent pad.

3. A spring boot made of flexible material adapted to be wrapped around a spring, a gromet connected lubricant container positioned within the boot, said gromet providing an opening for access to the interior of the container and means for closing the opening.

In testimony whereof I affix my signature. 85
GEORGE BITHEL PRICE.
